UNITED STATES PATENT OFFICE.

WILLIAM A. STOCKTON, OF PLEASANT HILL, LOUISIANA, ASSIGNEE OF TWO-THIRDS
TO WILLIAM DOWELL, PLEASANT HILL, LOUISIANA.

CULTIVATOR.

Application filed May 2, 1922. Serial No. 553,023.

To all whom it may concern:

Be it known that I, WILLIAM A. STOCKTON, a citizen of the United States, residing at Pleasant Hill, in the parish of Sabine and State of Louisiana, have invented a new and useful Cultivator, of which the following is a specification.

This invention relates to cultivators, and more particularly to cultivators of the 10 spring tooth type.

The primary object of the invention is to provide means for adjusting the tooth frames, so that the teeth supported thereby may be moved to operate at various angles 15 with respect to each other.

With the foregoing and other objects in view which will appear as the description proceeds, the invention resides in the combination and arrangement of parts and in 20 the details of construction hereinafter described and claimed, it being understood that changes in the precise embodiment of the invention herein disclosed, may be made within the scope of what is claimed, without departing from the spirit of the invention. 25

Referring to the drawings:

Figure 1 is a rear elevational view of a cultivator constructed in accordance with 30 the invention.

Figure 2 is a sectional view taken on line 2—2 of Figure 3.

Figure 3 is a plan view of the cultivator.

Figure 4 is an elevational view of the 35 cultivator, one of the tooth frames being moved.

Figure 5 is a detail view disclosing the tooth supports.

Figure 6 is a sectional view disclosing the 40 manner of supporting a tooth adjacent to tooth frames.

Referring to the drawings in detail, the harrow includes a body portion 5 which is formed with an opening 6 extending transversely therethrough, the opening being of a length to extend substantially the entire length of the body portion as shown by Figure 4 of the drawings. The forward end of the body portion 5 is formed with a plurality of openings 7, which openings accommodate the pins 8 carried by the movable securing member 9, which is formed with openings 10 to accommodate the usual bolt of a clevis, by means of which the power device may be hitched to the cultivator. 55

Extending through the body portion are bolts 11 which also extend through openings formed adjacent to the ends of the securing member 9, the upper ends of the bolts being supplied with washers 12 providing stops 60 for the upper ends of the coiled spring 13, the lower ends of the coiled spring contacting with the securing member 9 to normally urge the same downwardly.

As shown, the pins 8 which are carried by 65 the securing member 9 intersect the elongated openings 6, where they may have connection with the adjusting rods 14 to secure the forward ends of the adjusting rods in their adjusted positions on the body portion, 70 for purposes to be hereinafter more fully described.

The harrow also includes pivoted frame sections 15 and 16 respectively, each section comprising a forward bar 17 having an opening extending longitudinally thereof, the opening being indicated at 18 and provides a clearance for the reception of the forward ends of the teeth 19 of the harrow. 75

A rear member 20 forms a part of each section and includes spaced bars, between which bars are mounted the pivoted guide members 21, which guide members have extensions 22 positioned in openings formed in the spaced bars. The forward ends of 80 the teeth 19 are pivotally supported within the openings of the forward bars of the sections, so that the bars may pivot with respect to the teeth and allow the teeth to be adjusted with respect to each other. 85

Formed at the rear end of each of the adjusting rods 14 is an opening to accommodate the bolt 23 associated therewith, which bolt also extends through the forward bars of the respective section to pivotally secure 90 the rear ends of the adjusting rods 14 to the sections of the harrow. From the foregoing it will be seen that if it is desired to adjust the tooth supporting sections of the harrow, it is only necessary to move the securing member 9 upwardly against the tensions of the springs 13, removing the pins 8 from their openings. With the member 9 in this position, the forward ends of the adjusting rods 14 may be moved to move the sections 95 of the harrow to various positions, securing the frames at angles with respect to the body portion 5, adapting the harrow for use in harrowing plants planted at various distances apart. 100

At the rear of the body portion 5 is formed an opening to accommodate the bar 24 which is formed with a plurality of openings 25 to receive the transversely extending 5 pin 26 by means of which the bar 24 may be held in its positions of adjustment. At the lower end of the bar 24 is formed a head 28 which is secured to the rear end of the rearwardly extending bar 29 that 10 is secured to the under portion of the body 5 as at 30. The pin 26 is supported by the spring arm 31 so that the pin may be readily and easily removed to be positioned in the openings of the bar 24 to adjust the head 28. 15 This head 28 is especially designed for contacting with material tending to clog the cultivator teeth, to cause the cultivator to ride over the material.

Bars 32 connect the bars forming the sections of the cultivator, and relieve the teeth of the harrow of undue strain directed to the lateral sections. In order that the harrow may be properly guided, handles 33 are provided, which handles may be gripped by

the operator in the usual and well known 25 manner.

Having thus described the invention, what is claimed as new is:—

A harrow comprising a body portion, said body portion having a plurality of 30 openings, a securing member on the body portion and having a plurality of pins adapted to move within the openings, resilient means for normally holding the pins in the openings, tooth supporting sections piv- 35 otally mounted on the body portion, adjusting rods having connection with the sections and having their forward ends secured to the body portion by engagement with the pins, and curved harrow teeth supported by 40 the sections.

In testimony that I claim the foregoing as my own, I have hereto affixed my signature in the presence of two witnesses.

WILLIAM A. STOCKTON.
